MULTELEMENT HELIX ANTENNA

Arthur E. Marston and Mack Donald Acock,
Washington, D. C.

Application December 1, 1949, Serial No. 130,575

4 Claims. (Cl. 250—33.51)

(Granted under the act of March 3, 1883, as
amended April 30, 1928; 370 O. G. 757)

1

This invention relates in general to helical antennas and in particular to a novel helical antenna providing improved symmetry in the radiation pattern and circularity in the polarization of the radiation obtained therefrom.

It has been noted, that while the radiation obtained from conventional helical antennas may be approximately circular in polarization, it is found in practice, however, to be insufficiently circular for certain antenna applications, such as may be encountered in the jamming of enemy radar or in the transmission and reception of television signals.

Another difficulty encountered with the conventional helical antenna, operating as an end-fire antenna wherein the maximum radiation is along the longitudinal axis, is that the radiation pattern derived therefrom, for purposes of receiving or transmitting electromagnetic energy, is not symmetrical. This is of course a serious disadvantage for most any type of antenna use when it is desired that the pattern therefrom adequately cover a certain field.

The present invention provides a combination of circularly polarized helical elements arranged and disposed in a unique manner, as fully described hereinafter, about a common axis, and operable as a single end-fire antenna. The preferred embodiment of the present invention provides many advantages over that of a single helical antenna element; the most prominent advantages are with respect to improvements in the symmetry of the field radiation pattern obtainable from a single helix and to improvements in the circularity of polarization.

It is accordingly an object of the present invention to provide a new and improved helical antenna.

It is a further object of the present invention to provide a new and improved multi-element helical antenna offering an improvement in the symmetry of the field radiation pattern over that of a single helical antenna.

Another object of the present invention is to provide a new and improved multi-element helical antenna offering improved circularity of polarization for either transmission or reception over that generally offered by a single helical antenna.

Still another object of the present invention is to provide a new and improved multi-element helical antenna wherein the elements are disposed about a common axis to eliminate an array factor.

Further objects and attainments of the present

2

invention will become apparent upon a careful consideration of the following detailed description when taken in conjunction with the drawings in which:

5 Fig. 1 is a typical illustration of the preferred embodiment showing a pair of substantially identical helical elements disposed about a common axis in accordance with the present invention and

10 Fig. 2 is illustrative of the field radiation patterns obtainable from a conventional single helical antenna and the multi-element helical antenna shown in Fig. 1.

15 Referring in particular to Figure 1 there is illustrated a pair of helical antenna elements arranged in accordance with the teachings of the present invention. Helices 13 and 14 are of the end-fire type, wherein the maximum radiation of each helix is in the direction along its longitudinal axis, and the polarization of each helix is approximately circular. The helical antennas illustrated in Fig. 1 are hereinafter described for the purposes of transmission of electromagnetic energy but the principle of the present invention, as applied in the preferred embodiment, is equally as well applicable in an helical antenna operative for the reception of electromagnetic energy. Helical elements 13 and 14 are substantially identical, both resonant at the same frequency or band of frequencies at which they are end-fire, and both disposed on a common longitudinal axis indicated by dotted line 16. The antennas are centrally positioned on a ground plane 12 and are energized, by a two wire transmission line 20. Inner conductor 22 of transmission line 20 is connected to the first turn 18 of helix 13 and outer conductor 23 is connected to the first turn 17 of helix 14. The outer conductor 23 being the shield of transmission line 20 and which is also terminated in the ground plane 12.

20 25 30 35 40 45

We have discovered a property of the helical antenna with respect to the phasing thereof that bears a direct relationship to the angular orientation of the helices about their longitudinal axis. More particularly it has been proven, as an example, that with two helices energized in phase, and with the two helices oriented so that their first turns point in the same direction, there is a zero phase difference therebetween. However it was further shown that, if one of the helices is rotated about its longitudinal axis, say as per example again, by 90° there results a 90° phase difference between the two helices. This

phasing principle is true for any angular orientation distinction between any number of helices.

The converse of this phasing principle with respect to their angular orientation, and which is more directly applicable to the present invention, is equally true. That is if, for instance, two helical antennas are energized with an 180° phase distinction, then rotating one of the helices by 180° will restore the in phase radiation condition.

With a single helical antenna as a simulated single wire antenna, the field pattern obtainable therefrom is found to be asymmetrical about its longitudinal axis. This asymmetry is primarily caused by the asymmetry of the radiation pattern of a single turn of the individual helices. We have found, however, that this asymmetry can be corrected by interwinding a second helix with an axis common to the first helix. The second helix is identical with the first helix, that is having the same physical dimensions and accordingly the same resonant frequency. To permit interwinding of the two helices, to be operable as a double wire antenna in accordance with the principles of the present invention, the two helices must necessarily, therefore, be oppositely oriented.

Interwinding the helical elements about a common axis has shown to be more advantageous than if they were placed side by side as in any array. The most prominent advantage of coaxially interwinding the helices is eliminating the array factor, that is the phasing of the elements, as described herein, may be more readily carried forth by eliminating any phase distinction due to the spacing of the elements.

It is known in the art that when two antennas are energized in phase, the fields therefrom will add, and it is also known that when they are energized 180° apart the patterns from each antenna will be distinct with a null therebetween. To overcome the phase distinction between helices due to the necessary opposite angular orientation of the helices, as hereinbefore described, and to obtain a zero phase distinction between helices so that the fields therefrom add, the helices are energized 180° apart by the line 20. Any means known to the art, however, may be employed rather than the means shown to energize the helices in phase opposition.

The present invention is, of course, not to be limited to the number of helices shown in Fig. 1, moreover, the more helices employed (to a practical limit) the more symmetrical the pattern therefrom will be. The only requirement in employing two or more helices being that they must be energized with a phase distinction corresponding to the orientation distinction between helices. It was found, generally, that the best results are obtained when the helices are progressively oriented, that is, if four helices were employed they would be oriented, with respect to their common longitudinal axis, at 0°, 90°, 180° and 270°.

With reference to Fig. 2, there is shown a typical pair of antenna patterns A and B, pattern A being illustrative of a non-symmetrical radiation pattern substantially as that derived from a single helix antenna and pattern B being illustrative of the improved symmetrical pattern produced by the multi-element helical antenna of the present invention. The pattern A contains an accentuated minor lobe on one side of its axis and as here shown, this lobe is to the left of the axis. By employing two helical antennas

as described above, a symmetrical pattern as that shown in B is obtained.

Directly in accordance with the above outlined principle relating to improvements in the symmetry of the field radiation pattern, is the circularity of polarization. Improvement in circularity of polarization has been found to follow in the same manner, with respect to the helices, as the improvements in the symmetry of the field pattern.

10 A helical antenna constructed in accordance with Fig. 1 has a spacing between turns of .24 of the operating wavelength, at which they are end-fire, and the diameter of the turns is .31 of the operating wavelength. The number of turns was decided upon in accordance with the beam width desired and is not factor in determining the resonant frequency.

15 Although a certain specific embodiment of this invention has been herein disclosed and described, it is to be understood that it is merely illustrative of this invention and modifications may, of course, be made without departing from the spirit and scope of the invention as defined in the appended claims.

20 The invention described herein may be manufactured and used by or for the Government of the United States of America for governmental purposes without the payment of any royalties thereon or therefor.

25 What is claimed is:

1. An end-fire helical beam antenna system comprising a plurality of similar, resonant helical filament antennas interwound in the same direction about a common axis, each filament having a turn diameter greater than the turn pitch and being such that one turn length thereof substantially equals one wavelength at the operating frequency, one end of said filaments being open to cause said antenna to resonate at said operating frequency and the other end of said filaments being terminated in a feed system to produce a symmetrical single-lobe pattern of circularly polarized radiation.

40 2. An end-fire helical beam antenna system comprising a plurality of similar, resonant helical filament antennas interwound in the same direction about a common axis, each filament having a turn diameter greater than the turn pitch and being such that one turn length thereof substantially equals one wavelength at the operating frequency, one end of said filaments being open to cause said antenna to be resonant at said operating frequency, the first turn of each

45 of said filaments having a distinct angular orientation relative to said axis, and means connecting the other end of said filaments with an electrical phase distinction in accordance with said orientation distinction to produce a symmetrical single-lobe response pattern for circularly polarized waves.

50 3. An end-fire helical beam antenna system comprising a pair of similar, resonant helical filament antennas interwound in the same direction about a common axis, each filament having a turn diameter greater than the turn pitch and being such that one turn length thereof substantially equals one wavelength at the operating frequency, the turns of one of said helical filaments being arranged in spatial opposition with respect to the angular orientation of the other of said filaments about said axis, one end of said filaments being open to cause said antenna to be resonant at said operating frequency, and means connecting the other end of said filaments in

electrical phase opposition to produce a symmetrical single-lobe response pattern to circularly polarized waves.

4. An end-fire helical beam antenna system comprising a pair of similar, resonant helical filament antennas interwound in the same direction about a common axis, each filament having a turn diameter greater than the turn pitch and being such that one turn length thereof substantially equals one wavelength at the operating frequency, one end of each of said filaments being open, the first turn of each of said filaments having a distinct angular orientation relative to said axis, a ground plane for said pair of helices, coaxial transmission line means including an inner conductor connected to one of said pair of filaments and an outer conductor connected to the other of said filaments and said ground plane for energizing said pair of filaments with an electrical phase distinction in accordance with said orientation distinction to produce

a symmetrical single-lobe response pattern to circularly polarized waves.
